UNITED STATES PATENT OFFICE.

JOHN H. BENNETT AND ADRIAN I. MINER, OF SAN FRANCISCO,
CALIFORNIA.

ARC-LAMP.

No. 844,489.

Specification of Letters Patent.

Patented Feb. 19, 1907.

Application filed June 3, 1905. Serial No. 263,565.

To all whom it may concern:

Be it known that we, JOHN H. BENNETT and ADRIAN I. MINER, citizens of the United States, and residents of the city and county of San Francisco, State of California, have invented certain new and useful Improvements in Arc-Lamps; and we do declare the following to be a full, clear, and exact description of the same, such as will enable others skilled in the art to which it appertains to make and use the same, reference being had to the accompanying drawings, and the characters of reference marked thereon, which form a part of this specification.

15 Our invention relates to improvements in electric-arc lamps; and our object is to produce a simple, effective, automatic carbon-feed for said lamps and also to generally improve upon the style and arrangement of the lamps as now used. This object we accomplish by the peculiar construction and relative arrangement of parts hereinafter fully described and particularly pointed out in the claims appended.

25 In the drawings similar characters of reference indicate corresponding parts in all the views.

Figure 1 is a vertical section of our improved lamp. Fig. 2 is a sectional view taken on a line *x x* of Fig. 1. Fig. 3 is a sectional view taken on a line *y y* of Fig. 2. Fig. 4 is a perspective view of our improved carbon-clutch. Fig. 5 is a top view of the carbon-clutch shown in Fig. 4.

35 1 designates the frame of the lamp, and 2 the globe. Said frame 1 is provided with a removable bottom 1^a, secured in position by means of screws 1^b. 3 is a casing arranged at the top of the said frame 1 and provided 40 with a base 4 and a screw-cap 5 and wire connections 6.

7 is a brass tube arranged within the casing 3 and extending a short ways below the base 4, said tube being provided with a centrally-orificed top cap 8 and a similar centrally-orificed bottom screw-cap 9. Within the said tube 7 is arranged a carbon-clutch comprising a female member composed of a curved iron bar 10, provided with slightly-ovalized rings 11, and a male member composed of a curved iron bar 12, provided with slightly-ovalized rings 13, adapted to fit between the rings 11. The upper carbon 14 fits through the orifices in the caps 8 and 9

and the rings 11 and 13 and is provided with 55 a cap 15, to which is connected the current-wire 16.

Surrounding the tube 7 and resting on the base 4 is a coil 17, suitably connected to the wire 18, carrying the current to the bottom 60 carbon. Between the said coil and the said tube, on opposite sides thereof, are two narrow strips of soft iron 19, for the purpose as will be shown.

In the lower end of the casing 1 is secured 65 a conductive tube 20, open at both ends and threaded at the lower end to receive a nut 21 and a cap 22, the wire 18 being connected to said tube between said nut and said cap. To insert the lower carbon, the cap 22 is removed and the carbon inserted upward into the tube 20 and secured therein by means of a small set-screw 24. The cap 22 is then screwed on, which excludes the air as is necessary. This construction is particularly 70 advantageous, as in many forms of the old-style lamps the carbon is inserted through the top of the globe, and thus very often the 75 globes are broken.

To clean the lamp, the bottom may be removed by loosening the screws 1^b.

The operation of our improved carbon-feed is as follows: When the current is turned on, assuming the parts to be in the position shown in Fig. 3, the members 10 and 12 will 85 be repelled and caused to grip the carbon, due to these members being magnetized, while the members 19 will also be magnetized, the members 10 and 12 gripping the carbon and holding the same stationary. As the 90 carbon burns out the resistance increases, thus allowing the clutch to slightly release and permit the carbon to feed down to the required point. The clutch automatically adjusts itself to varying amperage—for instance, if the lamp is wound to a certain 95 voltage and amperage and that amount is suddenly increased after lighting the lamp, the clutch will enlarge the arc, thus throwing in resistance, which will prevent the lamp 100 from being burnt out. The iron strips 19 concentrating the magnetism in the opposite sides of the tube 7 keeps the clutch well centered, and thus holds the carbon steady and true this result being due to the fact that 105 the force is exerted equally at substantially opposite points of the tube.

We have now entered into a detailed de-

scription of the construction and relative arrangement of parts embraced in the present and preferred embodiment of our invention. We do not desire, however, to be understood

5 as confining ourselves to such specific detail, as such changes and modifications may be made in practice as fairly fall within the scope of our claims.

Having thus described our invention, what 10 we claim as new and useful, and desire to secure by Letters Patent, is—

1. In an arc-lamp a brass tube provided with top and bottom centrally-orificed caps, a two-part carbon-clutch of magnetic material arranged within said tube, a current-carrying coil surrounding said tube, two small strips of soft iron between said coil and said tube one opposite the other, a carbon disposed between the two parts of said clutch, 15 as specified.

2. In an arc-lamp a seat for the bottom carbon composed of a conductive tube open at both ends and secured to the bottom of the

lamp-frame, a small set-screw in the side of said tube, and a bottom screw-cap for said tube extending over said set-screw, as set forth.

3. In an arc-lamp, the combination with a frame, of a solenoid-coil, carried by said frame, a tube of non-magnetic material disposed within said coil, strips of magnetic material disposed longitudinally of the coil between the inner surface of the coil and the said tube, a two-part carbon-clutch composed of longitudinally-disposed bars each carrying rings 30 adapted to embrace a carbon, said clutch being arranged within said tube.

In testimony whereof we have signed our names to this specification in the presence of two subscribing witnesses.

JOHN H. BENNETT.
ADRIAN I. MINER.
